JOHN B WIARD.

By *Albert B. Davis* ATTY.

UNITED STATES PATENT OFFICE.

JOHN B. WIARD, OF LYNN, MASSACHUSETTS, ASSIGNOR TO GENERAL ELECTRIC COMPANY,
A CORPORATION OF NEW YORK.

MEANS FOR COOLING ELECTRIC MOTORS.

No. 920,798.

Specification of Letters Patent.

Patented May 4, 1909.

Application filed February 23, 1907. Serial No. 358,768.

To all whom it may concern:

Be it known that I, JOHN B. WIARD, a citizen of the United States, residing at Lynn, in the county of Essex and State of Massachusetts, have invented certain new and useful Improvements in Means for Cooling Electric Motors, of which the following is a specification.

On account of the small clearance between 10 the armature and the field members of induction motors, it is difficult to cool these members in the usual way by forcing currents of air between them. This is particularly true in the case of induction motors having high 15 resistance armature windings.

The object of the present invention is to provide means whereby motors of the type referred to may readily be kept cool.

To the above end I make the armature conductors hollow, that is, in the form of tubes, and provide means for forcing cooling currents of air through the interior of these conductors. Thus the cooling medium comes 20 into direct contact with the surfaces of the 25 parts in which the heat is generated.

The various features of novelty whereby my invention is characterized will be herein- 30 after particularly pointed out in the claims; but for a full understanding of the invention 35 in its various aspects, reference may be had to the following detailed description taken in connection with the accompanying drawing, wherein—

Figure 1 is a longitudinal section taken 35 through the axis of an induction motor arranged in accordance with a preferred form of my invention; Fig. 2 is an end elevation of this motor with a portion of the bonnet broken away so as to more clearly show the 40 end of the armature; and Fig. 3 is a perspective view of the fan or blower which is associated with the armature, parts being broken away to more clearly show the interior construction.

Referring to the drawing, 1 indicates an induction motor having a primary or field member 2 and a secondary or armature member 3. The field member may take any usual or preferred form, as may also the armature member except to the extent herein- 50 after indicated. The armature is of the squirrel-cage type having its conductors 4 arranged just within the periphery of the core member 5, and short-circuited by rings 6 and 7 which respectively connect the ends of

the conductors together at the ends of the armature. The armature conductors are made hollow, as shown, and a blower 8 is provided at one end of the armature for producing a continuous flow of air through the interior of 60 these conductors while the machine remains in operation. The blower may take any usual form, but it is preferably of the type which forces the air positively through the tubular conductors; it may therefore be 65 made advantageously in the form of a centrifugal blower which receives air at its axis and discharges it at its periphery into and through the tubes.

A convenient method of constructing and 70 supporting the blower consists in utilizing the end ring 7 as the closed side of the blower. This ring is therefore made in the form of a disk having a central opening 9 which is not 75 much larger in diameter than required for the passage of armature shaft. An annular flange 10 projects laterally from the periphery of the disk-like end-ring and, secured to this flange in a plane somewhat removed from the end-ring, is a second disk-like member 11 80 having a central opening 12 which is larger 85 in diameter than the opening in the member 7. Arranged between the members 7 and 11 are a plurality of radial vanes 13 which extend from the opening 12 to points adjacent 90 the ends of the tubular armature conductors. By this arrangement there is formed at one 95 end of the armature an annular chamber 14 connected to the ends of the tubular conductors, into which chamber air taken in through the opening 12 of the blower is discharged 100 when the armature begins to rotate. The air passes from this chamber through the tubular conductors and is discharged at the opposite end of the armature. By properly proportioning the parts, the temperature of the motor may be kept within any desired limits. Furthermore, the armature conductors may be made very thin so as to offer extremely high resistance without danger of overheating.

What I claim as new and desire to secure by Letters Patent of the United States, is,—

1. In an induction motor, an armature having hollow conductors, and a blower 105 mounted on said armature in operative relation to said conductors arranged to force air through the conductors when the motor is in operation.

2. In an induction motor, an armature 110

2
having hollow conductors, short-circuiting rings at opposite ends of the conductors, and a blower supported upon one of said rings in position to produce a flow of air through said conductors when the motor is in operation.

3. In an induction motor, an armature having hollow conductors and short-circuiting rings at the ends of the conductors, one of said rings being in the form of a disk, a second disk, and fan blades arranged between the two disks.

4. In an induction motor, an armature having hollow conductors and short-circuiting rings at the ends of the conductors, one of said rings being in the form of a disk, a second disk connected with the short-circuiting disk so as to form an annular chamber communicating with the interior of the conductors, and radial vanes arranged between said disks.

5. In an induction motor, an armature having hollow conductors and short-circuit-

ing rings at opposite ends of the conductors, one of said short-circuiting rings being in the form of a flanged disk, a second disk connected to the flange of the short-circuiting disk so as to form therewith an inclosing chamber about the ends of the armature conductors, and radial vanes arranged between said disks and extending to points adjacent the ends of the conductors.

6. In an induction motor, an armature having hollow conductors, a blower mounted on said armature, having a chamber which communicates with the interior of each of the conductors and arranged to force air through the conductors when the motor is in operation.

In witness whereof, I have hereunto set my hand this twentieth day of February, 1907. 40
JOHN B. WIARD.
